A. B. LAMB.
SAFETY RAZOR,
APPLICATION FILED MAR. 25, 1921.

Patented Nov. 21, 1922.

By Harry H. Semmes

Attorney

Patented Nov. 21, 1922.

UNITED STATES PATENT OFFICE.

ARTHUR B. LAMB, OF CAMBRIDGE, MASSACHUSETTS.

SAFETY RAZOR.

Application filed March 25, 1921. Serial No. 455,443.

To all whom it may concern:

Be it known that I, ARTHUR B. LAMB, a citizen of the United States, residing at Cambridge, in the county of Middlesex and State of Massachusetts, have invented certain new and useful Improvements in Safety Razors, of which the following is a specification.

This invention relates to safety razors and more particularly to the kind having a two-edged blade which is adjustable and provided with a clamping handle of the bolt type.

Among the objects of this invention is to provide a safety razor which is easily assembled and disassembled, highly efficient and of simple construction.

A further object is to provide a simple mechanism for adjusting the width of the guard to the varying widths of the blade, said mechanism being separate and distinct from that for clamping the blade in position.

In safety razors the blades vary not only as regards the keenness of the edge, but, some blades are slightly narrower than others, and thence the protection afforded by the guard varies. A variation of as much as a half millimeter will very considerably affect the likelihood of cutting oneself. I have devised a very simple and easily constructed device which permits the extension or withdrawal of the guard by a millimeter or two on each side by a very simple and convenient operation.

Reference is to be had to the accompanying drawing wherein a specific embodiment of my invention is illustrated.

Figure 1 is an end view of my device when assembled.

Fig. 2 is a detail plan view showing the flexible, adjustable guard.

Fig. 3 is a detail plan view of the slotted back plate.

Fig. 4 is a bottom plan view of my device in assembled condition.

The device comprises a handle 1 which screws on to a front plate 2. The razor blade 3 is positioned between the front plate 2 and a flexible guard 4, and on the other side of the guard 4 there is placed the back plate 5. This plate 5 is provided with slots 6 and perforations 7, 8 and 9 through which the studs (not shown) on the front plate 2 pass and thereby keep this back plate 5 in

position. The flexible guard 4 consists of the serrated side members 10 and the bowed transverse members 11 which are substantially parallel with each other and are preferably integral with the side members 10. These members 11 are provided substantially at the center with projections 12 and when the razor is in assembled condition these bowed transverse members 11 are positioned in the slots 6 of the back plate 5, and longitudinal movement of the guard 4 is therefore prevented. The projections 12 extend beyond the slots 6 and are adapted to be engaged by a milled nut or screw sleeve 13.

It will be seen that by bearing upon the projections 12 the flexible guard 4 will tend to flatten thereby, outwardly moving the serrated side members 10 in a direction substantially perpendicular to the cutting edge of the blade, and when pressure upon the projections 12 is removed the side members 10 will come together. The milled nut 13 therefore affords a convenient means for widening and contracting the guard and thereby regulating the protection afforded by the guard.

It will be further seen that this movement of the guard 4 by the nut 13 is entirely independent of the rest of the device and does not result in movement of other parts of the razor. The blade 3, front plate 2 and back plate 5 are clamped and held in place by screwing the handle 1 on to the front plate 2. The blade 3 is neither tightened nor loosened by the movement of the guard by the sleeve nut 13. It is desirable to have the central stud on the front plate 2 threaded so that the handle 1 may be screwed upon it.

It is to be understood that my invention is not limited to the specific details set forth in the foregoing arrangement and construction and since numerous modifications may be effected without departing from the spirit and scope of my invention I desire that only such limitations be imposed as are indicated in the following claims.

I claim as my invention:

1. In a safety razor, a front plate, a back plate, a flexible guard, a blade between said front plate and said guard, said guard being disposed between said blade and said back plate, means for clamping said blade and guard between the front and back plates and means independent of said clamping means and comprising a friction nut thread-

ed upon the handle of said razor for sliding said guard in a direction substantially perpendicular to the cutting edge of said blade.

2. In a safety razor, a front plate, a back plate, a flexible guard, a blade between said front plate and said guard, said guard being disposed between said blade and said back plate, means for clamping said blade and guard between the front and back plates and means independent of said clamping means for sliding said guard in a direction substantially perpendicular to the cutting edge of said blade.

3. In a safety razor, a front plate, a back plate, a flexible guard, a blade between said front plate and said guard, said guard being disposed between said blade and said back plate, means for holding said blade substantially fixed relative to the front and back plates, means for clamping said blade and guard between the front and back plates and means independent of said clamping means for sliding said guard in a direction substantially perpendicular to the cutting edge of said blade.

4. In a safety razor, a front plate, a back plate, a flexible guard, a blade, a handle provided with a single means for clamping said blade, guard and front and back plates and means comprising a friction nut upon said handle for sliding said guard in a direction substantially perpendicular to the cutting edge of said blade.

5. In a razor, a flexible element constituting a safety guard for the cutting edges of said razor and comprising serrated side members joined by bowed, transverse members, a handle and a threaded member upon said handle adapted to engage said bowed members and means for guiding the movement of said side members in a direction substantially perpendicular to the cutting edges of said razor when said threaded member acts upon said bowed, transverse members.

6. In a safety razor, a flexible guard comprising serrated side members, transverse members joining said side members, said transverse members being bowed and having substantially central projections for engaging with a movable threaded member on the handle of the razor.

7. In a safety razor, a flexible guard com-

prising a pair of serrated side members, a pair of substantially parallel transverse members joining said side members, said transverse members being bowed and engaging with a friction nut threaded upon the handle of said razor and means for guiding the movement of said side members in a direction substantially perpendicular to the cutting edges of the blade of the razor when said friction nut acts upon said bowed, transverse members.

8. In a safety razor, a front plate, a slotted back plate, a flexible guard comprising serrated side members and transverse members joining said side members, a blade between said front plate and said guard, said guard being disposed between said blade and said back plate and said transverse members being bowed and passing through the slots in said back plate.

9. In a safety razor, a front plate, a slotted back plate, a flexible guard comprising a pair of serrated side members and a pair of substantially parallel transverse members integral with and joining said side members, a blade between said front plate and said guard, said guard being disposed between said blade and said back plate and said transverse members being bowed, passing through the slots in said back plate and engaging a movable threaded member on the handle of the razor.

10. In a safety razor, a front plate, a slotted back plate, a flexible guard comprising a pair of serrated side members and a pair of substantially parallel transverse members integral with and joining said side members, a blade between said front plate and said guard, said guard being disposed between said blade and said back plate, said transverse members being bowed, having substantially central projections and passing through the slots in said back plate, a handle provided with means for clamping said blade and guard between the front and back plates and means comprising a friction nut threaded upon said handle for engaging the transverse members upon said guard and sliding the serrated side members substantially perpendicular to the cutting edge of the blade.

In testimony whereof I affix my signature. 105
ARTHUR B. LAMB.
